COMBINED LATCH AND LOCK

Berthold R. Thiele, Milwaukee, Wis., assignor to
 E. R. Wagner Manufacturing Company, Milwaukee, Wis., a corporation of Wisconsin

Application February 21, 1944, Serial No. 523,202

5 Claims. (Cl. 70—70)

This invention relates to an improved combined latch and lock of the character shown in my prior Patent 2,233,115, issued February 25, 1941, and one object of the invention is to improve and simplify the construction shown in said patent and to render the same more rugged and durable.

Other objects and advantages reside in certain novel features of construction, arrangement and combination of parts which will be hereinafter more fully described and particularly pointed out in the appended claims, reference being had to the accompanying drawing forming a part of the specification, and in which:

Fig. 1 is a fragmentary view in front elevation illustrating a combined latch and lock embodying the present invention applied to the hinged sections of a box;

Fig. 2 is a similar view with the cover of the latch housing removed to show the construction; and

Fig. 3 is a view similar to Fig. 2 showing a slightly modified construction.

Referring to the drawing, the numeral 10a designates the body of a box and the numeral 10b the lid or cover thereof. The latch housing is shown generally at 11 and comprises a base plate 11a marginally flanged as at 11b and a cover 11c which fits down over the flange of the base plate and is secured thereto in the manner described in my aforesaid patent or in any other convenient manner. The base plate may likewise be secured to the body of the box in the manner described in my aforesaid patent or in any other convenient manner. The latch bolt designated generally at 17 is pivoted as at 19 upon the base plate 11a within the housing and is provided with a latching or locking projection 18. The latch bolt is biased into latching position by means of a slideable combined spring and lock bolt 25 supported and fulcrumed intermediate its ends upon lug 33 struck up from the base plate 11a, supported and guided for slideable movement only adjacent one end 23 between similarly formed lugs 22 and normally free and in engagement with the latch bolt at its other end 28. The fulcrum lug 33 and the lug 22 opposed thereto are so organized and related with respect to the latch bolt when in latching position that it is necessary to flex the spring in order to position the same on the lugs with its free end in engagement with the latch bolt as shown in the drawing. A locking projection 27 is formed in the spring adjacent the fulcrum lug 33 and inter-

mediate such projection and the guided portion 23 of the spring, the spring is provided with a V-shaped portion 26 designed to coact with a key 31 which may be inserted through a keyhole 31a provided in the cover of the casing and also interengaged with an opening 11d formed in the base plate of the casing to center and support the rear end of the key. A lug or stud 46 is struck up from the base plate 11a just in advance of the free end of the spring 25 when in the full line position shown in the drawing. When the combined spring and bolt 25 is in its retracted position as shown in full lines in the drawing, the free end 28 of the spring simply serves as a spring to retain the latch in latching position. To lock the latch the key is inserted in the keyhole 31a and rotated clockwise in the construction shown in Fig. 2, or counter-clockwise in the construction shown in Fig. 3, whereupon the bit of the key engages one wall of the V-shaped portion 26 formed in the spring and will force the spring toward the right in Fig. 2, or upwardly in Fig. 3, the locking projection 27 riding over the lug 33 and through its resiliency snapping into position on the opposite side of the lug and retaining the spring in its shifted position until it is again operated by rotation of the key. By this shifting of the spring 25 to the dotted line position, the free end 28 thereof is projected over the edge of the lug 46, thus blocking unlatching movement of the latch bolt and locking the bolt in latching position. Unlocking of the latch is effected by a reverse rotation of the key which shifts the spring to the left in the construction of Fig. 2, or downwardly in the construction of Fig. 3, retracting the free end thereof to the full line position leaving the latch free for normal latching operation.

The lid of the box is provided with a part co-operable with the combined latch and lock comprising a sheet metal stamping 6 suitably secured to the lid by fastening means 7 or the like and provided with a hook 8 adapted to enter a slot 11e provided in the upper part of flange 11b of the latch housing and interengage with the latch projection 18 of the latching bolt 17. The hook 8 and latching projection 18 are shaped and dimensioned as shown in the drawing so as to be self-latching when the lid of the box is closed.

If desired, the guided portion 23 of the spring shown in Fig. 2 may be extended as shown in dotted lines at 21 so as to underlie the hook 8 and thus serve to cushion the latter in its latching engagement with projection 18 and to lift the lid of the box upon disengagement of the latch. The spring shown at 21a in Fig. 3 serves the same

function and purpose. In this case, however, the spring 21a is a separate element held in proper position within the housing by means of a clip 48 struck up from the marginal flange 11b of the base plate 11a. For convenience in unlatching the latch when the spring 25 is retracted from locking position, the latch bolt may be provided with a stud 41 projected through a slot 42 in the cover of the housing and providing a finger grip by which the latch bolt may be moved to unlatched position against the tension of the free end of the spring. In lieu of a finger grip exposed on the face of the housing in this manner, the manual release may take the form of a lateral projection extending through a slot in and exposed exteriorly of one of the lateral walls of the housing as shown in dotted lines at 44.

The construction and operation of the combined latch and lock shown in Fig. 3 is substantially the same as that shown in Fig. 2 and for convenience the same reference numerals have been applied. The chief difference between the constructions of Figs. 2 and 3, apart from the lid-lifting spring arrangement, resides in the dimensioning of the housing, the housing of Fig. 2 being of major transverse extent, while that of Fig. 3 is of major vertical extent requiring a slight rearrangement of the parts. The principle of operation in each, however, is the same. A further distinction as between the two constructions resides in the shape of the latch bolt. In Fig. 2 the latching projection and the means for manual unlatching are mounted on the same side of the pivot 19, whereas in Fig. 3 the latch bolt is more of the order of a bell crank with the latching projection on one side of the pivot and the manual operating means on the other. It will be obvious that either type of latch bolt may be used in either construction.

If desired, a lug 32, struck up from the base plate or otherwise formed, may be employed and positioned to coact with the nose of the V-shaped portion 26 of the spring 25 to assist in guiding the action of the spring in its locking and latching positions and during shifting from one position to the other.

While I have shown and described two constructions in which the invention may be advantageously embodied, it is to be understood that the constructions shown have been selected merely for purpose of illustration and that various changes in the size, shape, and arrangement of the parts may be made without departing from the spirit of the invention or the scope of the appended claims.

I claim:

1. A combined latch and lock comprising a

10 casing, a latching bolt mounted therein, a bodily shiftable spring mounted in said casing and free to flex at one end and held against flexure at the other and engaged at its free end with said bolt to bias the same into latching position, a stud in said casing adjacent the free end of said spring, and key coacting means for shifting said spring to position the free end thereof between said stud and bolt to block the latter against unlatching movement.

15 2. A combined latch and lock comprising a casing, a latch bolt mounted therein, a bodily shiftable spring mounted in said casing and supported at one end and intermediate its ends for sliding movement and being unsupported and free to flex at its other end and engaged at such end with said bolt to bias the same into latching position, a stud in said casing adjacent the free end of said spring, said spring intermediate its points of support being formed for coaction with the key for shifting said spring to position the free end thereof between said stud and bolt to block unlatching movement of the latter.

20 3. In a combined latch and lock, a casing, a latch bolt mounted therein, a bodily shiftable spring, a plurality of supports therefor including a fulcrum intermediate the ends of the spring, a guide at one end of the spring and a stud at the other, the spring at the latter end engaging the bolt and being free to flex to permit unlatching movement of the bolt, the spring having a portion intermediate the fulcrum and the guide to cooperate with a key to shift the spring to a position between the stud and the bolt to prevent flexure of the spring and thereby lock the bolt against unlatching movement.

25 4. In a combined latch and lock, a casing, a latching bolt mounted therein, a guide and a fulcrum support in said casing, a spring engaging against said guide at one end and against said bolt at its other end and against said support intermediate its ends in such wise that the same is under tension in all positions of said bolt, a locking stud adjacent the bolt engaging end of said spring, and key coacting means for bodily shifting the spring to pass the latter end thereof between the stud and bolt to lock the bolt.

30 5. In a combined latch and lock, a casing, a latch bolt therein, a guide and a fulcrum in said casing, a spring engaging against said guide at one end and tensioned over said fulcrum intermediate its ends and engaged against said bolt at its other end, a block normally beyond the latter end of said spring, and means for shifting said spring to project said end between said block and bolt to lock the latter.

BERTHOLD R. THIELE.
